(57) **CLAIM**

The ornamental design for a dispenser, as shown and described.

DESCRIPTION

FIG. 1 is a perspective view showing a new design for a dispenser;

FIG. 2 is a front view thereof, the rear, left side, and right side views being identical thereto; and,

FIG. 3 is a top view thereof, the bottom view being a mirror image.

The portions of the dispenser in FIGS. 1-3 shown in broken lines are included to show features that form no part of the claimed design.

1 Claim, 2 Drawing Sheets
